DOOR HOUSING FOR LOCOMOTIVE
STOKERS

William Thompson Hanna, Cincinnati, Ohio

Original application June 18, 1928, Serial No.
286,222. Divided and this application June 11,
1936, Serial No. 84,612. Renewed July 1, 1939

6 Claims. (Cl. 110—104)

This invention relates to stokers for use on locomotives and steamboats. More particularly it relates to a housing member for such stokers as convey coal forwardly from a trough beneath a coal hopper in a tender to the fire-box of a locomotive. In the present invention the housing embraces the firing opening at the fire-box and itself has a hand firing opening. This is a division from my co-pending application, Serial Number 286,222, filed June 18, 1928, and resulting in Patent No. 2,004,001.

One of the objects of the invention is to provide such a fire door housing for use in connection with a stoker of the class described which is adapted to aid in directing the flow of fuel therethrough toward the firing opening in such a way as to offset tendency to clog or to create a back pressure.

Another object of the invention is to provide a fire door housing of the class described, having a firing opening providing a clear view of the condition of the fire bed and the action or movement of the fuel through the housing, and permitting unobstructed use of a shovel, a firing rake, or hook, so that the flow of fuel may be assisted manually in the case of clogging by foreign material by merely opening the fire door, and without displacing or interfering with the operation of any of the stoker mechanism.

Another object of the invention is to provide a fire door housing which houses and supports various fuel manipulating mechanisms of the stoker and which permits easy access to these parts whereby the maintenance of the same is greatly simplified.

A further object of the invention is the provision of a fire door housing for a stoker of this type which permits the ready adaption of such a stoker to any locomotive with a minimum of alterations in the stoker design, by virtue of including all of the components of the stoker, with the exception of the conduit, conveyor means, and motive power, in this housing, and by reason of the wide flexibility in regulation permitted by these controls therein included.

These and other apparent objects and advantages are obtained by the means described in the following specification and disclosed in the accompanying drawings, wherein:

Figure 1 shows a vertical sectional view of a stoker mechanism embodying this invention, taken substantially on a longitudinal center line;

Figure 2 is a vertical transverse section of the same, taken substantially on a line 2—2 of Figure 1;

Figure 3 is a horizontal section of the same, taken substantially on a line 3—3 of Figure 1;

Figure 4 is a side elevation partially in vertical longitudinal section, showing a stoker of this character co-acting with a locomotive and a tender;

Figure 5 is a top plan view of the interior of the housing of Figure 1; and

Figure 6 is a vertical section taken on line 6—6 of Figure 3.

In the drawings, as shown in Figures 1 to 4, numeral 1 represents the backhead of a locomotive fire-box having a conventional firing opening 2 within which is located fuel distributing mechanism, generally indicated at 18, for distributing fuel over the fire bed. Embracing this opening, and rigidly mounted on the backhead, is a fuel or fire door housing 3. Connected to the base of the housing, and forming a downwardly rearwardly projecting extension, is a conduit 4 through which fuel moves upwardly into housing 3. The extension 4 increases in cross-sectional area from its lower to upper extremities, so that fuel moving up through it is constantly relieved of pressure at its sides (see Figure 3) and tendency of the fuel to clog while passing therethrough is offset. Extending rearwardly from conduit 4 (Figure 4) is conduit 6, which in turn is connected to the front end of a hopper 8 beneath a tender 9. Suitable conveyors 7 in hopper 8, and 5 in conduit 6, serve to move the fuel forwardly into the housing 3.

The connections between hopper 8 and conduit 6, and between conduit 6 and extension 4, are of the ball and socket type. The conduit 6, in addition, has a sliding joint in the extension 4. These joints provide a substantially universal joint connection between the conduit 6, hopper 8 and extension 4 whereby changes in the relative positions, or a displacement of the tender from the locomotive, are accommodated.

As shown in Figure 4, conveyor 7 is driven by a gear 10 which is driven by a shaft 11 suitably mounted for rotation on the frame of the trough 3 and carrying a gear (not shown) which engages the gear 10. The shaft 11 has operative engagement with a steam motor, or other source of motive power, 12, through suitable connection as, for example, the telescopic shaft 13. The fuel manipulating means 14 and 15, hereinafter described, are also driven by motor 12 through shafts 60.

Referring now to the construction of the housing 3 and elevating conduit 4, by making the elevating conduit 4 and the housing 3 in separate

pieces I am able to adapt a single size housing, which is relatively expensive to manufacture in different sizes, to different sizes and types of locomotives by simply using an extension 4 of the desired length.

The housing 3 chosen to illustrate the invention provides a housing for fuel manipulating means 14 and 15 designed to improve the stocking efficiency of a stoker. An advantage of such manipulating means is that they insure the fuel flowing to the distributing means 18 in a regulated stream. The manipulating means act upon the column of fuel rising in the housing to spread the fuel and transform it into form relatively thinner than the bulk of the fuel in the conduit 4 and to regulate the presentation of the fuel to the fire-box. In thinning the fuel in this manner, its form is changed as to thickness, or density, consistency, etc., and the fuel reaches the distributing mechanism in a manner and condition conducive to efficient distribution over the fire.

In the particular form shown the fuel manipulating means or conditioning device comprises a pair of tapered rotary vanes or worms 14 and 15 which are suitably journaled in cap plates 16 and 17 forming part of the side walls of the housing and are preferably so positioned relative to the housing and the firing opening as to cause relatively little resistance to the flow of fuel.

To facilitate the flow of the fuel through the housing 3 and to assist further in the operation of the tapered worms 14 and 15, the housing 3, Figures 5 and 6, is provided with recesses generally indicated at 111 and 112 respectively, formed in either side of the wall of the housing adjacent the backhead 1. The recesses 111 and 112 have conically shaped concave fuel supporting surfaces 113 and 114 respectively, the surfaces being concentric with surfaces containing the respective peripheries of the vanes 14 and 15. In this way the vanes 14 and 15 are, in effect, recessed in the front wall 3e of the housing 3, and to some extent are removed from the direct path of the fuel as will be hereinafter described in greater detail.

The surfaces 113 and 114 intersect the surface of the forward wall 3e of the housing 3 to form edges or ledges 115 and 116 respectively, over which the fuel rising from the extension 4 flows into the recesses 111 and 112 to be acted on by the worms 14 and 15 respectively as will be hereinafter described. Thus by providing the recesses in the housing the worms are recessed out of the direct line of flow of the fuel up the throat of the housing and so do not interfere with the flow. The fuel, as described hereinafter, simply flows up and is either undermined by the worms or falls over onto them.

In order more effectively to manipulate the fuel in the manner above described, the housing is preferably shaped to further the tendency of the fuel to flow over the edges 115 and 116 into the respective recesses 111 and 112 and into the range of the fuel conditioning and spreading devices 14 and 15. This is accomplished in the present embodiment by slanting the back wall 3d (Figure 1) toward the forward wall of the housing, generally indicated at 3e, and at the same time increasing the distance between the side walls of the housing 3 to insure the increasing cross-sectional area. This sloping rear wall 3d causes a forward pressure to be exerted on the rising fuel column, causing it to fall forwardly and sidewardly over the edges 115 and 116 into

the recesses 111 and 112 and into the range of the fuel manipulating elements 14 and 15.

Referring to Figures 2 and 3, worms 14 and 15 are shown as tapering toward their unmounted or free ends. With this construction the fuel handling capacity of each worm is greater at its mounted end (where the vane is largest) than at its free end (where the vane is smallest) and so, as fuel moves from the mounted toward the free end of each worm, it is caused to move away from the worms and is delivered over the ledge 3a.

From the foregoing it is clear that the fuel entering the housing 3 from the extension 4 is acted upon by the devices 14 and 15 which transform the fuel issuing from the extension 4 into form relatively thinner than the bulk of fuel in the extension 4 and regulate the presentation of the fuel over the ledge of spillway 3a from whence it flows to the distributing mechanism 18.

The housing 3 is provided with an opening 3c in the rear side thereof, and embracing this opening is a conventional form of fire door plate 65, upon which may be mounted the usual automatic fire door (not shown), such as, for example, the Franklin Butterfly type. As shown in Figures 1 and 2, the fire door opening 3c is positioned in the rear wall of the housing 3 in such a way that it is just above and to the rear of the stream of fuel entering the housing 3 from the extension 4 and the lower part of the housing 3. Further, the firing opening 3c is substantially aligned with the firing opening 2 in the backhead 1. With this construction and arrangement of the fire door opening, many new and highly advantageous results are obtained. For example, the opening affords a simple means for examination of the flow of fuel from the conduit to extension 4 past the spreading devices 14 and 15 over the ledge 3a onto the blast chamber 18 and over the fire bed itself. Further, this arrangement provides easy access to the fuel rising from the extension 4 in the event of large lumps of fuel or extraneous material clogging the passageway at this point. Thus, with this construction and arrangement I overcome the disadvantage existing in mechanical stokers heretofore used for locomotives, which have not afforded such easy access to the path of the fuel just as it enters the firing opening.

The distributing mechanism comprises a distributor plate 31 and a blast chamber 19, provided with a plurality of high pressure steam jets 19b coming out of a series of fingers 19a arranged in a fan formation and a sheet low pressure blast 22 located below the high pressure jets 19b along the bases of the fingers 19a. The blast chamber 19 is provided with arms 18a and 18b which support it and serve as conduits for the passage of the steam thereto.

The distributor plate 31 coacts with the steam blasts to distribute the fuel over the fire bed in an efficient manner. It is made adjustable in position to accommodate it to particular demands. The adjustment is made by a crank shaft 34 connected with a handle 34a. A link 36 connects an arm 35 on the shaft with the plate 31. Crank shaft 34 is suitably journaled in bearings on the housing 3.

Referring again to the housing 3, it is provided with means for varying the effective lateral length of the ledge 3a, for controlling the flow of fuel passing over said ledge. While this result may be accomplished in various ways, in the

present illustration I have provided laterally adjustable members 37—38, slidably mounted in the side walls of the housing 3 and resting upon the ledge 3a, thereby constituting in effect a continuation of said ledge. The members 37 and 38 5 may be independently adjusted laterally with respect to the housing so that they not only control the effective length of the ledge 3a, but also move the effective length of said ledge to one side or 10 the other of the firing opening, to direct a greater volume of fuel to the right or to the left sides of the blast chamber 18, as desired. The operating means for these members 37 and 38 comprise levers 39 and 40 (Figure 2) pivotally supported 15 upon pins 41 and 42, mounted in lugs 3b extending from the housing 3. The levers are arranged to have operating engagement with the members 37 and 38 through pins 43 and 44. The rotating vanes 14 and 15 are driven by suitable gearing 20 (not shown) in gear housings 51 mounted on the bearing caps 16 and 17.

In operation of this stoker mechanism, the coal flows from the tender 9 to the trough 8, beneath the deck of the tender, and is transferred therefrom forwardly to the locomotive by the rotation of the conveyors 7 and 5, the latter delivering the fuel through the extension 4 into the housing 3, whereupon, due to the contours of said housing, the fuel is presented to the rotating vanes 14 and 30 15 and the further movement of fuel is controlled by the action of the said vanes. The vanes act on the fuel to condition it by spreading, leveling, deflecting and directing it in such a manner that it passes over the ledge 3a in a plurality of laterally moving continuous streams. The fuel, thus directed over the ledge 3a, falls upon and flows over the blast chamber 18 which tends to screen it and distribute it over the fire-bed. The larger lumps of fuel, flowing over the ends of the 40 fingers 19a, are projected over the fire by the high pressure steam jets 19b and the smaller particles are allowed to fall onto the distributor plate 31, from which they are scattered over the fire by means of the blasts of steam emitted from 45 the low pressure jets 22.

While I have shown and described a particular construction embodying this invention as applied to a locomotive stoker, it is to be understood that the same is for the purpose of illustration only, and that I am not limited to the 50 detailed features thereof, as it is understood that the construction may be variously modified and altered without departing from the spirit and scope of the invention, as set forth in the appended claims.

I claim:

1. In a stoker mechanism having moving fuel-conditioning and regulating means, the combination with a fire box having a fuel entrance, 60 of a housing having a forward wall adapted to embrace the fuel entrance, having a fuel outlet in said forward wall communicating with said fuel entrance and being approximately coextensive therewith, having a hand-firing opening in its rearward wall substantially aligned with said fuel outlet, having a fuel inlet below said fuel outlet, and having means for supporting and housing the moving fuel-conditioning and regulating means in said housing so that approximately 65 all of the fuel-contacting portions of said conditioning and regulating means lie below said fuel outlet whereby the locomotive may be hand-stoked and the operation of the fuel-conditioning and regulating means observed without in- 70 terfering with the operation of the stoker.

2. In a stoker mechanism having moving fuel-manipulating means, the combination with a fire box having a fuel entrance in its back wall, of a housing having a forward wall adapted to embrace the fuel entrance, said wall having a fuel outlet adapted to communicate with said fuel entrance and being approximately coextensive therewith, said housing having a hand-firing opening in a rearward wall thereof, substantially aligned with said fuel outlet, said housing having wall portions therein below said outlet adapted to recess the moving fuel-manipulating means, and having a fuel inlet below and to the rear of said recessed portions, and the rearward wall of said housing being slanted forwardly toward said forward wall to give the fuel moving through the housing from said inlet a greater forward component. 10 15

3. In a stoker for a locomotive the combination with a fire box having a fuel entrance, of a housing having a forward wall adapted to embrace the fuel entrance, having a fuel outlet in said forward wall communicating with said fuel entrance and being approximately coextensive therewith, having a hand-firing opening in its rearward wall substantially aligned with said fuel outlet, having a fuel inlet at the lower extremities of said forward and rearward walls and below said fuel outlet, the rearward wall of said housing inclining toward said forward wall 30 from said inlet to cause the fuel moving through said housing between said forward and rearward walls from said inlet to change its direction of flow toward said fuel outlet and the side walls diverging upwardly from said fuel inlet to give a cross-sectional area greater than that of said fuel inlet whereby the flow of fuel is directed toward said fuel entrance, and clogging and back-pressure are prevented. 35

4. In a stoker for a locomotive, the combination with a fire box having a fuel entrance in its back wall, of a fuel discharge housing provided with an upwardly extending forward wall adapted to be mounted in juxtaposition to the back wall and fuel entrance and arranged to discharge fuel to said fuel entrance, said housing being provided with a rearward wall extending above said fuel entrance and having a hand-firing opening therein approximately co-extensive with and aligned with said fuel entrance, side walls connecting said forward and rearward walls, said housing having a fuel inlet disposed below said fuel entrance and hand-firing opening to receive fuel moving in an upward direction between the side walls and the said forward and rearward walls and discharging to said fuel entrance, and said hand-firing opening lying above and overlooking such fuel movement, whereby the fire box may be hand-stoked through said hand-firing opening and the fuel movement observed without interfering with the movement of fuel from said inlet through said fuel entrance. 45 50 55

5. In a stoker for a locomotive, the combination with a fire box having a fuel entrance in its back wall, of a housing having a forward wall 65 provided with a fuel outlet adapted to communicate with the fuel entrance, having a rearward wall provided with a hand-firing opening substantially aligned with said fuel outlet, having a fuel inlet disposed in a plane below said fuel outlet, and having a fuel passageway extending in an upward direction from said fuel inlet to said fuel outlet on the median line of said housing and between said forward and rearward walls, so that the movement of the fuel as it leaves the 70 75

passageway and emerges through said outlet may be readily observed through said hand-firing opening.

6. In a stoker for a locomotive, the combination with a firebox having a fuel entrance in its back wall, of a fuel housing provided with an upwardly extending forward wall having a fuel outlet adapted to communicate with the fuel entrance and mounted in juxtaposition to the back wall so as to enable fuel passing through said outlet to move into said entrance, said housing being provided with a rearward wall extending above said outlet, side walls connecting said forward and rearward walls, said housing having a fuel inlet disposed below said fuel outlet to receive fuel moving in an upward direction from

said fuel inlet and through a fuel passageway disposed on the median line of said housing and between said forward and rearward walls and said side walls and subsequently discharging through said outlet, said rearward wall having a hand-firing opening therein approximately co-extensive with and aligned with said fuel entrance and lying above and overlooking the fuel moving through said passageway toward and through said outlet whereby the firebox may be hand-stoked through said hand-firing opening, and the said movement of the fuel readily observed without interfering with its flow through the housing.

WILLIAM THOMPSON HANNA. 15
